UNITED STATES PATENT OFFICE

JOHN I. MICHAELS AND LESTER R. WATKINS, OF WICHITA, KANSAS, ASSIGNEES TO
THE WATKINS MANUFACTURING COMPANY, OF WICHITA, KANSAS, A CORPORATION OF KANSAS.

CASTING JIG.

Application filed June 26, 1926. Serial No. 118,792.

Our invention relates to improvements in jigs for casting metal bearings and has particular reference to a jig which may be used to advantage in casting bearings in various articles, but which is designed especially for casting Babbitt bearings in cylinder blocks of internal combustion engines, our purpose being to provide a jig which is simple in construction, relatively cheap and easy to manufacture, which is compact and capable of being quickly and easily manipulated, which is adjustable to accommodate bearings of different lengths, which includes self-contained means for securing it in operative position upon an article to be supplied with a bearing, which is of such construction that Babbitt or other metal may be poured therein with facility, and which includes means whereby a minimum amount of roughness is left upon a poured bearing to be dressed off.

Our inventive idea is capable of embodiment in different mechanical structures, certain of which are shown in the accompanying drawings, but it is to be understood that the structures shown are intended merely as disclosures of the essential features and novel characteristics of our invention in certain preferred forms and that its scope is as defined in the appended claims.

In the drawings, wherein like characters of reference denote corresponding parts in the different related views:—

Fig. 1 is an elevation of one preferred form of our improved jig showing same mounted in operative position upon a cylinder block;

Fig. 2, an elevation at right angles to Fig. 1 with parts of the jig and the cylinder block shown in section;

Fig. 3, a top plan view of the jig as seen in Fig. 2;

Fig. 4, a transverse section on the line 4—4 of Fig. 4;

Fig. 5, a view similar to Fig. 1 showing another preferred form of our improved jig;

Fig. 6, an elevation at right angles to Fig. 5 with parts of the jig and cylinder block shown in section;

Fig. 7, a top plan view of the jig shown in Fig. 6;

Fig. 8, an elevation of the hopper end of the mandrel of our improved jig; and

Fig. 9, a top plan view of the mandrel.

Referring to the drawings in detail, first to Figs. 1 to 4, it will be observed that our improved jig includes essentially a mandrel 10 of circular cross section and of suitable length having a collar 12 secured thereto in any suitable manner at its lower end from which projects a handle 12' and at its upper end being slightly enlarged in diameter throughout a portion of its length as indicated at 14.

A band 16 is secured in any preferred manner around the enlargement 14 of mandrel 10 and a circumferential portion of the latter approximating 120° is cut away as indicated at 18 to provide, between the mandrel and said band, a segmental orifice 20 through which molten Babbitt or other metal is adapted to be introduced into a cavity to produce a bearing as will hereinafter appear.

The upper end of the enlargement 14 of mandrel 10 is inclined downwardly, as indicated at 22, towards the orifice 20 thereby to provide in conjunction with band 16, a hopper into which molten Babbitt or other metal is adapted to be poured whereby it may flow through orifice 20 into the cavity to be filled to form a bearing.

For a purpose which will presently appear the upper face 22 of enlargement 14 is inclined at such an angle that its lower edge intersects the side wall of mandrel 10 slightly above the plane of the lower edge of band 16.

Extending from the side of mandrel 10 opposite the orifice 20 and below band 16 is an enlargement 24 which may be formed as an integral part of said mandrel, but which for convenience in manufacture, preferably is formed either as a part of band 16 or as an element apart from said band and mandrel as herein shown and secured to the latter in any preferred manner as, for example, by means of screws 26. This enlargement is of a length somewhat greater than the length of the longest bearing it is contemplated casting by means of our jig and, as shown, it extends one-half the way around mandrel 10 and terminates in longitudinally extending flat faces 28, 28.

Slidably mounted on mandrel 10 below the enlargement 24 is a sleeve 30 provided with a handle 32 and having a semi-circularly shaped upward extension 34 thereon which extension is disposed oppositely with respect to enlargement 24 and terminates in 110

longitudinally extending flat faces 36, 36 which slidably engage the faces 28, 28 of enlargement 24, said sleeve 30 being urged constantly towards its uppermost limit of 5 sliding movement on mandrel 10 by an expansion coil spring 38 which surrounds said mandrel between said sleeve and the collar 12 and reacts from the latter against the former.

10 In the use of our improved jig just described sleeve 30 is moved by means of handle 32 downward on mandrel 10 against the force of spring 38 until the lower face of band 16 and the upper face of the extension 34 are spaced apart a distance somewhat greater than the length of the part in which a bearing is to be casted. The jig then is applied to the part—a cylinder block 40 for example—in which a bearing is to be 15 casted by engaging the lower face of band 16 with one end of the part 42 that is to receive the bearing and releasing sleeve 30, so that spring 38 may force the upper face of extension 34 into engagement with an opposite end of the part that is to receive the bearing, the jig thus being clamped and retained in place upon the bearing receiving part by said spring. Usually bolt receiving 20 openings 44 are formed in the bearing receiving part adjacent to the semi-circularly shaped bearing receiving recess 46 therein, and by using the outer face of enlargement 24 adjacent to the flat faces 28, 28 thereof as guides the jig may be positioned by means 25 of these holes to dispose the portion of mandrel 10 between the band 16 and the upper end of extension 34 concentric and spaced with respect to recess 46, it being understood that for a given size of bearing to be 30 casted mandrel 10 will be of a diameter somewhat less than the diameter of the recess 46, so that when the flat faces 28, 28 are arranged in abutting relation with the outer face of the bearing receiving part to 35 either side of the recess 46 therein, a semi-circularly shaped cavity will remain between said mandrel and the part, said cavity being closed at its lower end by the upper end of extension 34, at its sides by the faces 40 28, 28 of enlargement 24, and partially closed at its top by the lower edge of enlargement 14 and band 16, orifice 20 thus remaining the sole means whereby molten metal may be introduced into or whereby it may escape 45 from cavity 46.

With our jig operatively associated with a bearing receiving part 42 as just described and as clearly shown in Fig. 2, molten Babbitt or other metal is poured into the hopper 50 provided by band 16 and the upper end of the enlargement 14 of mandrel 10 and allowed to flow through orifice 20 into the cavity 46 until the latter is completely filled. After an elapse of sufficient time to permit 55 the metal to harden the sleeve 30 is moved

downward on mandrel 10 by means of handle 32 until the upper end of extension 34 is spaced somewhat from the lower end of the part 42, it being noted in this connection that when the upper end of extension 34 has been 70 moved below the lower end of enlargement 24 the sleeve 30 may be rotated to engage the upper end of said extension beneath said enlargement whereby the sleeve 30 may be locked against upward movement on mandrel 10. When extension 34 has been disengaged from enlargement 24 the entire jig is given an upward movement by means of handle 12' with the result that any surplus metal remaining in the hopper at the upper 75 end of the mandrel is broken away from the metal filling cavity 46 at the upper end of orifice 20, leaving said cavity filled with an accurately casted bearing having only a minimum amount of roughness at its upper end to be dressed off, it having been found in practice that by having the inclined upper face 22 of enlargement 14 intersect the side of mandrel 10 adjacent to orifice 20 slightly 80 above the lower face of band 16 the surplus metal in the hopper will be broken away from the bearing at said point of intersection rather than within the limits of the casted bearing.

Obviously our jig as described in the foregoing is intended only for casting bearings without end flanges, but as shown in Figures 5 to 9 elements may be added to said jig to adapt it for casting bearings either with or without end flanges. In other words, the jig shown in Figures 5 to 9 structurally and in mode of operation is the same in all essential respects as the jig shown in Figures 1 to 4, but includes in addition to the parts shown in Figures 1 to 4 a pair of bands 48, 50 the former embracing band 16' and the latter embracing sleeve 30'. Band 16' is provided with an inclined slot 52 which receives a pin 54 projecting from the inner face of band 48, so that upon rotation of said band 48 about 105 band 16' in one direction said band 48 will be moved, as a result of the cam action between said pin and slot connection to the position shown in Figure 6 with its lower edge disposed below the lower edge of band 16', while upon rotation thereof in an opposite direction said band will be moved to a position with its lower edge flush with the lower edge of band 16', a handle 56 on said band 48 providing a convenient means of 110 manipulating same.

Sleeve 30' is provided with a slot 58 inclined preferably in a direction opposite to slot 52, said slot 58 receiving a pin 60 projecting from the inner face of band 50, so 115 that upon rotation of said band upon said sleeve in one direction said band will be moved to a position as shown in Fig. 6 with its upper edge disposed above the upper edge of extension 34', while upon rotation thereof 120

in an opposite direction same will be moved to a position with its upper edge flush with the upper edge of said extension 34', said band 50 being provided with a handle 62 whereby it may conveniently be so manipulated.

When the bands 48, 50 are moved to the positions shown in Figure 6, their lower and upper ends, respectively, will engage the part 42' to be supplied with a bearing, leaving a lateral space or cavity at each end of cavity 46' into which molten metal will flow to produce end flanges on the casted bearing. When, on the other hand, the bands 48, 50 are moved to bring their lower and upper faces, respectively, flush with the lower and upper faces, respectively, of band 16' and extension 34' the structure so far as results which may be obtained therefrom are concerned will be essentially the same as the structure shown in Figures 1 to 4.

From the foregoing description considered in connection with the accompanying drawings it is believed that the construction mode 25 of operation and advantages of our improved jigs will be fully understood. We desire to point out, however, that various changes and desirable additions may be made in and to the structures shown within 30 the spirit and scope of our invention as defined in the appended claims.

We claim:

1. A bearing casting jig comprising a mandrel having a hopper at the upper end thereof terminating in an orifice opening adjacent to the side of said mandrel, and means carried by said mandrel for cooperation with a bearing receiving machine part to produce a bearing receiving cavity about 40 a portion of said mandrel.

2. A bearing casting jig comprising a mandrel having a laterally extending surface adjacent to its upper end for contact with a machine part that is adapted to have a bearing casted therein, said mandrel having a hopper at the upper end thereof formed by inclining the upper surface of said mandrel, said hopper terminating in an orifice opening adjacent to the side of said mandrel, and means carried by said mandrel for cooperation with a bearing receiving machine part to produce a bearing receiving cavity about a portion of said mandrel, the said inclined upper surface of said mandrel intersecting the side wall thereof above said laterally extending surface whereby surplus metal remaining in said hopper after a bearing has been casted will be broken off from the bearing upon upward movement of the jig with respect to the bearing receiving machine part outside the defining limits of the bearing.

3. A bearing casting jig comprising a cylindrical mandrel having a hopper at the upper end thereof terminating in a dis-

charge orifice opening adjacent to the side of said mandrel, a laterally extending surface on said mandrel adjacent to its upper end for contact with an end surface of a bearing receiving machine part, a member 70 slidable on said mandrel having a laterally extending surface for contact with an opposite end surface of the bearing receiving machine part, means cooperating with the laterally extending surfaces on said mandrel and said member to provide a bearing receiving cavity when said jig is mounted upon a bearing receiving machine part, and means constantly urging said member towards the laterally extending surface on said mandrel.

4. A bearing casting jig comprising a cylindrical mandrel having an enlargement at its upper end, a band surrounding said enlargement and extending above the upper end thereof to provide a hopper, a portion of said enlargement being cut away to provide a discharge orifice between said band and said mandrel, and means carried by said mandrel for cooperation with a bearing receiving machine part to provide a bearing receiving cavity in communication with said hopper through said orifice.

5. A bearing casting jig comprising a cylindrical mandrel, having a hopper at its upper end terminating in a discharge orifice adjacent to the side of said mandrel, a horizontally extending lateral surface on said mandrel near its upper end for contact with an end surface of a bearing receiving machine part, a pair of longitudinally extending lateral surfaces on said mandrel for contact with other surfaces of a bearing receiving machine part, a member 95 slideable on said mandrel having a horizontally disposed lateral surface for contact with the other end surface of a bearing receiving machine part, and spring means constantly urging said member towards the upper end of said mandrel.

6. A bearing casting jig comprising a cylindrical mandrel, having a hopper at its upper end terminating in a discharge orifice adjacent to the side of said mandrel, a horizontally extending lateral surface on said mandrel near its upper end for contact with an end surface of a bearing receiving machine part, a pair of longitudinally extending lateral surfaces on said mandrel for contact with other surfaces of a bearing receiving machine part, a member slideable on said mandrel having a horizontally disposed lateral surface for contact with the other end surface of a bearing receiving machine part, and spring means constantly urging said member towards the upper end of said mandrel, said member having longitudinally extending lateral surfaces in sliding engagement with the longitudinally extending lateral surfaces on said mandrel whereby said

member normally is held against rotation on said mandrel.

7. A bearing casting jig comprising a cylindrical mandrel having a hopper at its upper end terminating in a discharge orifice adjacent to the side of said mandrel, a horizontally extending lateral surface on said mandrel near its upper end for contact with an end surface of a bearing receiving machine part, an enlargement on said mandrel having a longitudinally extending surface for contact with another surface of a bearing receiving machine part, a member longitudinally movable on said mandrel, and having a horizontally extending lateral surface for contact with the other end surface of a bearing receiving machine part, and means constantly urging said member towards the upper end of said mandrel, said member being rotatable whereby its lateral surface may be engaged beneath the lower end of said enlargement.

8. A bearing casting jig comprising a cylindrical mandrel having an enlargement at its upper end, a band surrounding said enlargement and cooperating with the same to provide a hopper having a discharge orifice opening adjacent to the side of the mandrel, a semicircularly shaped enlargement on said mandrel below said band, a sleeve slidable on said mandrel below said enlargement, a semicircularly shaped upward extension on said sleeve having surfaces slidably engaging surfaces of said enlargement, a collar on the lower end of said mandrel, and an expansion coil spring disposed between said collar and said sleeve urging the latter constantly towards the upper end of the mandrel.

9. A bearing casting jig comprising a mandrel and means carried by said mandrel

adjustable whereby bearings may be casted by said jig with or without end flanges.

10. A bearing casting jig comprising a mandrel having a hopper at the upper end thereof terminating in a discharge orifice adjacent to the side of said mandrel, a horizontally extending lateral surface on said mandrel near its upper end, a sleeve longitudinally movable along said mandrel and having a horizontally extending lateral surface below said first mentioned lateral surface, and a pair of bands one of which surrounds the part having said first mentioned lateral surface and the other of which surrounds said sleeve, said bands being adjustable to dispose their adjacent end surfaces flush with and also inwardly with respect to said first mentioned lateral surface and the lateral surface of said sleeve.

11. A bearing casting jig comprising a mandrel provided with a hopper at its upper end terminating in a discharge orifice adjacent to the side of said mandrel, a band surrounding an upper end portion of said mandrel, a second band surrounding said first mentioned band, one of said bands having an inclined slot therein and the other having a pin engaged in said slot whereby rotation of the second mentioned band moves same longitudinally of said first mentioned band, a sleeve slidable on said mandrel, a band rotatable on said sleeve, a pin and inclined slot connection between said sleeve and said last mentioned band, and means constantly urging said sleeve towards the upper end of said mandrel.

In testimony whereof we hereunto affix our signatures.

JOHN I. MICHAELS.
LESTER R. WATKINS.
